FOOD DISPLAY PACKAGE

Jack V. Cline, San Diego, Calif., assignor to
Tee-Pak, Inc.

Continuation-in-part of design application Ser. No. 9,869,
Dec. 20, 1967. This application Oct. 4, 1968, Ser. No.
13,849

Term of patent 14 years

Int. Cl. D9—04
U.S. Cl. D9—239

FIG. 1

FIG. 2

FIG. 4

FIG. 3

FIG. 1 is an isometric view of a food display package, FIG. 2 is a view in elevation of the food display package observed from the right rear portion of FIG. 1,

FIG. 3 is a plan view of the food display package shown in FIG. 2, and

FIG. 4 is a view in section of the food display package taken on the line 4—4 of FIG. 3.

The food display package comprises a cylindrical container and top or closure therefor, formed of a clear, transparent plastic, and provided with a display jacket secured to the container as illustrated in FIG. 4.

This application is a continuation-in-part of design application Ser. No. 9,869, filed Dec. 20, 1967, and now abandoned.

I claim:

The ornamental design for a food display package, substantially as shown and described.
